DRAFTING RAILINGS AND STAIRS

卷之三

Specification of Letters in Particular Cases of the Law.

Application filed November 27, 1933. Serial No. 661,111.

To all whom it may concern:

Be it known that I, Joseph K. Blum, of the city, county, and State of New York, have invented certain new and useful Improvements in Disintegrating Apparatus, of which the following is the specification:

My invention relates to improved flour
beating apparatus of the type having a
plurality of beaters or beaters mounted
in a revolving head and caused to rotate
from the head by centrifugal force, and
the machine is in operation.

In operating such devices it is frequently desirable to have the outer periphery of the hammers move in close proximity to certain portions of the casing in order to obtain the maximum efficiency. This makes adjustment of the hammers or beaters with respect to the axis of the rotation of the main flywheel very difficult, if not, in fact, impossible, because there is a considerable danger of impinging the hammers on the sides. It is necessary that the construction be extremely simple in view of the character of the work, and that it be exceedingly simple and reliable as far as possible.

In the accompanying drawings, which form a part of this specification, Fig. 1 is a side elevation of a portion of a grating apparatus in which my improvements are incorporated. The casing is not shown, since it is not concerned in the improvements contemplated by my invention, and any suitable type of casing may be used. Fig. 2 is a transverse sectional view on line II-II of Fig. 1. Fig. 3 is a perspective view on a somewhat enlarged scale of one of the said devices for adjustably mounting the beaters or beaters upon the bead. Fig. 4 is a fragmentary perspective view showing a modification. Fig. 5 is a fragmentary sectional view showing a further modification.

Referring to the drawings in detail, the numeral 1 designates the main driving shaft which may be mounted in suitable bearings, not shown. Upon this shaft are mounted two fixed hubs 2 and 3 which are respectively provided with the flanges or heads 4 and 5. The hubs 2 and 3 are fixed to the shaft longitudinally in any suitable manner and are caused to rotate with the shaft by the key 6. Between these two hubs are two sets of hubs 7 and 8 which are supported in a slide along the shaft, but which are caused

to a less and less degree of fineness. It is this fact which makes adjustability such a desirable feature in the construction of this type of apparatus. When such wear occurs 5 in my improved device, it is only necessary to remove the split collar 11-12 by loosening the nuts 18, and then to slide the hubs 7-8 toward each other along the shaft 1, thereby withdrawing the heads or flanges 9 and 10 from the studs 25. This action will 10 release the cams so that the cams and the connected studs may be withdrawn from the heads or flanges 4 and 5 and turned through 90° or 180° as may be desired, and then re- 15 inserted into the heads 4 and 5, whereupon the other two flanges or heads are replaced, the split collar again bolted in position and the device is once more ready for operation. It will be obvious that the turning of the 20 cams through 90° or 180° will permit the hammers or beaters to progress away from the shaft 1 through the action of the cam surfaces, and that the square studs entering the square holes in the two sets of flanges or 25 heads will lock the cams in the desired new position. This change in the effective eccentricity of the cams will place the hammers or beaters into such a position that the outer periphery of the bars 19 is again in its 30 proper relation with respect to the casing when the hammers or beaters assume the position shown in Fig. 1 under the influence of centrifugal force. The wear is thus effectively compensated. It will be evident, of 35 course, that by changing the number of sides of the studs 24 and 25, finer adjustment and a greater number of degrees of adjustment may be obtained. In Fig. 1 I have shown the parts in their normal initial position, 40 so that the eccentricity α is in its most remote position with respect to the main shaft 1. The limiting position, or position of maximum adjustment with this type of cam and stud, will obviously be obtained when 45 the cams are each rotated through 180°.

In Fig. 4 I have shown a modification in which the cam 23 is provided with a main stud 28 of circular cross-section and a supplementary locking pin 29 which is adapted 50 to enter one of a series of circular holes 30 in one of the heads or flanges, these holes being equidistant from the center of the stud 28. It will be obvious that adjustment of the cam may be obtained by placing the 55 pin 29 in any one of the several holes 30, thereby varying the effective eccentricity of the cam. The fineness of the adjustment will depend upon the number of holes 30 provided.

60 Fig. 5 illustrates a further modification in which the inwardly projecting stud 25 is similar to that already described, while the outwardly projecting stud is replaced with a stud of circular outline 31 entering a 65 circular hole 32 in the outer fixed flange 4 or

5, as the case may be. The stud 25 has projecting inwardly from it an extension 33 of circular cross-section such that it may be inscribed within the periphery of the stud 25. In adjusting this type it is only necessary to slide the movable flange 9 or 10, as the case may be, inwardly into the position illustrated by the dotted lines in Fig. 5 and then to rotate the cam through the desired angle in any suitable manner, as by introducing a thin spanner wrench between the leg 20 of the hammer or beater 9 or 10 as the case may be, whereupon the movable flange 9 or 10 may be restored to its normal position, thus locking the cam in place through 75 the engagement of the lug 25 with the non-circular hole 27 in the flange 9 with which it engages.

While I have illustrated and described only certain specific embodiments of my device, I realize that it is susceptible of wide application, and I do not desire to be limited to the precise structure shown and described.

Having thus described my invention, what I claim is:

1. In a disintegrator, a rotary member, a fixed head and a laterally movable head mounted thereon, a hammer and means for adjustably mounting said hammer upon the rotary member, including a cam journaled in and supporting said hammer, said cam being supported by said heads and having a locking means engaging one of said heads and held in adjusted position thereby. 90
2. In a disintegrator, a driving shaft, a fixed head on said shaft, a movable head adapted to slide longitudinally on said shaft but rotating therewith, a hammer and means for adjustably mounting said hammer between the heads, including a cam and opposed projections therefrom one of which is non-circular adapted to engage, respectively, with the fixed and movable head. 100
3. In a disintegrator, a driving shaft, a fixed head thereon, a movable head thereon adapted to slide longitudinally on said shaft but rotating therewith, a hammer and means for adjustably mounting said hammer upon said heads, including a cam journaled in said hammer and a non-circular projection extending longitudinally beyond said cam and adapted to be located in fixed, adjusted position by said fixed and movable heads. 110
4. In a disintegrator, a main driving shaft, a pair of fixed heads thereon, a pair of movable heads mounted between said fixed heads and adapted to slide longitudinally along said shaft but rotating therewith, a U-shaped hammer having legs 125 adapted to enter between the adjacent fixed and movable heads, means for adjustably mounting said hammer upon the heads, and spacing means for locking said movable heads against sliding on said shaft. 130

5. In a disintegrator, a driving shaft, a pair of fixed heads thereon, a pair of movable heads mounted between the fixed heads and adapted to slide longitudinally along said shaft but rotating therewith, a U-shaped hammer having legs entering between the adjacent fixed and movable heads, means for adjustably mounting said hammer upon said heads, including a cam having a locking member engaging one of said heads but releasable by sliding said movable head away from said fixed head and spacing means for retaining said movable heads in locked operative position.
- 10 6. In a disintegrator, a driving shaft, a pair of fixed heads thereon, a pair of movable heads mounted between the fixed heads and adapted to slide longitudinally along said shaft but rotating therewith, a U-shaped hammer having legs entering between the adjacent fixed and movable heads, means for adjustably mounting said hammer upon said heads, and a split collar for locking said movable heads against sliding along said shaft and away from said fixed heads.
- 15 7. In a disintegrator, a shaft, a pair of fixed heads thereon, a pair of movable heads mounted between the fixed heads and adapted to slide longitudinally along said shaft but rotating therewith, a hammer having legs adapted to enter between adjacent pairs of fixed and movable heads, means for mounting said legs upon said heads, said means being releasable by moving the inner heads toward each other, and means for locking said movable heads in fixed operative position to clamp the hammer in place.
- 20 8. In a disintegrator, a shaft, a pair of fixed heads thereon, a pair of movable heads mounted between the fixed heads and adapted to slide longitudinally along said shaft but rotating therewith, a hammer having legs adapted to enter between adjacent pairs of fixed and movable heads, means for mounting said legs upon said heads, said means being releasable by moving the inner heads toward each other, and a split collar for locking said movable heads in fixed operative position to clamp the hammer in place.
